UNITED STATES PATENT OFFICE.

EDWARD G. BLUMENFELD, OF BROOKLYN, NEW YORK, ASSIGNOR TO LA SALLE BRASS & BRONZE WORKS, INC., A CORPORATION OF NEW YORK.

DESIGN FOR A CONSOLE TABLE.

Application filed August 2, 1928. Serial No. 27,673. Term of patent 3½ years.

To all whom it may concern:

Be it known that I, EDWARD G. BLUMENFELD, a citizen of the United States, and a resident of the city of New York, borough of Brooklyn, in the county of Kings and in the State of New York, have invented a new, original, and ornamental Design for a Console Table, of which the following is a specification, reference being had to the accompanying drawing, forming part thereof, in which

The figure is a perspective view of a console table showing my new design.

I claim:

The ornamental design for a console table, as shown.

Dated, New York city, July 28, 1928.

EDWARD G. BLUMENFELD.
